ABSTRACT OF THE DISCLOSURE

A ceramic convactor for converting a cooking unit into a temporary heater. The convactor has a venturi section and circumferentially spaced louvers to accelerate and uniformly distribute heated air or gas flowing upward into the convactor, the outside surface also acting as a radiant heater.

BACKGROUND OF THE INVENTION

Boats, trailers, camps and apartments often contain no heating facilities or marginal heating facilities because they are intended either for moderate climates or for seasonal use. Yet these places normally provide cooking facilities which include gas, electric or volatile liquid burners. There is a need for an economical way to convert a cooking burner into an auxiliary or temporary household heating unit which will increase the distribution of heated air throughout an enclosure.

Although prior art devices for increasing the radiant effectiveness of a gas flame with an emissive surface or for increasing the convective action of a gas heater are well known, these devices are generally designed to be incorporated as a permanent or integral part of a heating unit. They are usually adapted to function properly with only one kind of heat source.

Accordingly, one object of the present invention is to provide a compact supplemental device to increase the convective and radiant heating from a source of heated air.

Another object of the invention is to provide a separate convactor to convert a cooking unit into a household heating unit on a temporary basis.

DRAWING

These and many other objects will become apparent by reference to the following description, taken in connection with the accompanying drawing, in which the single figure is a horizontal elevation drawing, partly in cross-section, illustrating the convactor in its preferred form.

SUMMARY OF THE INVENTION

Briefly stated, the invention comprises a conduit, open at the top and bottom for the passage of heated air therethrough, having a central venturi section for accelerating the vertical flow, circumferentially spaced ports or louvers for inducing convective flow radially outward and upward, and having a heat radiating emissive outer surface.

DESCRIPTION

Referring now to the drawing, the convactor, shown generally at 1, rests on top of an ordinary cooking burner 2 having either heating elements or supporting grillwork elements 3, depending on the type of heat source, which is immaterial to the present invention. The only requirement is that elements 3 be spaced to allow passage of heated air or combustion gases freely upward into the convactor 1.

The convactor body in its preferred form is round, open at both ends, and generally conical from top to bottom. The outer wall 4 defines a flow passage with a

2

gradually converging section 5, a more abruptly converging section 6, a narrow neck 7, and a diverging section 8. Flow sections 6, 7 and 8 together form a central venturi passage which is surrounded by a relatively thick wall portion 4a.

Around the body of the convactor is a series of equally spaced holes 9 extending upward at an angle through the wall 4. These are preferably formed within suitably located protuberances 10, so that flow directing louvers 11 are formed thereby. The openings to louvers 11 are preferably located at the juncture or transition between the two, convergent sections 5 and 6.

An additional feature is the provision of an internal ledge 12 which, though not essential to the heating operation, is of great utility in stacking the units during production or storage. The ledge 12 is slightly larger in diameter than the top of the convactor so that a number of units will nest, and may either be continuous, as shown, or interrupted.

The convactor is preferably manufactured from a castable refractory material, of which there are many available types. The refractory used should be capable of withstanding repeated cycles of heat and cold. A porous, highly emissive surface is employed, rather than a reflective surface, in order to increase the heating effectiveness of the unit by radiation.

The exact dimensions of the convactor are not critical, yet certain dimensions and angles have been found to be desirable in practice to obtain the best results. A very effective unit has been developed which is 8 inches in height, 7 inches in diameter at the bottom narrowing to $\frac{3}{4}$ inch in diameter at the neck and opening back out to 4 inches diameter at the top. The included angles of the passages on either side of the neck are between 80° and 85° , although a range of 75° to 90° may be satisfactory, depending on the type of heat source. There are four louvers opening about halfway up the convactor in $\frac{1}{4}$ inch slits.

OPERATION

The convactor is placed on a cooking unit which acts as a source of heated air or hot gas. The natural upward current is accelerated by passage through the venturi section and caused to "mushroom" out through the surrounding space by the diverging top section. As the heated air expands and is crowded toward the venturi section, a slight pressure increase at the entrance to the converging section 6, aided by an aspirating effect due to air moving up around the outside surface of the convactor, causes a portion of the inside gas to flow through the louvers 11. This induces turbulent mixing and convective currents which fan upward and outward from the unit to warm the surrounding air. The heated air inside the convactor body also increases the temperature of the ceramic emissive refractory material of the wall which radiates heat from its exterior surface to the surrounding area.

EXAMPLE

A comparative test was made in a house trailer of 2500 cubic feet using a propane cooking stove. The use of the convactor described on one cooking burner raised the temperature of the air from 50° F. to 70° F. in 17 minutes. Without the convactor, four cooking burners and the oven required 32 minutes to achieve the same temperature rise.

Thus there has been disclosed a simple and economical means of furnishing supplemental heating by means of a unique convactor which is placed temporarily over an ordinary cooking unit. The convactor, by means of venturi and louvers, greatly enhances convective heating and by its ceramic walls provides radiant heating surfaces

as well. Other modifications will naturally occur to those skilled in the art and it is intended to cover all such modifications within the scope of the invention.

What I claim as new and desire to secure by Letters Patent of the United States is:

1. A convactor comprising a hollow member with an annular wall defining a flow passage therethrough and open at the top and bottom, said convactor passage including a bottom convergent section, an intermediate section of greater convergence, a venturi neck section, and a top divergent section, said sections being adjacent and coaxial with one another, said member also defining a plurality of circumferentially spaced openings through said wall and disposed near the juncture between said convergent sections.

2. The combination according to claim 1, wherein said convactor wall defines a plurality of external protuberances at the location of said openings and arranged to provide louvers for the openings which are directed in an upwardly direction.

3. The combination according to claim 1, wherein

said intermediate convergent section and said divergent section each have an included angle between 75° and 90°.

4. The combination according to claim 1, wherein said convactor wall defines internal ledge means at the juncture of said convergent sections and of a greater diameter than the top of the member so as to support the convactor in nesting fashion on top of another like convactor.

5. The combination according to claim 1, wherein said convactor is an integral member of castable refractory material of high emissivity.
